Robert M. McKenna

UNITED STATES PATENT OFFICE.

ROBERT MCKENNA, OF WHITE, TENNESSEE.

SPEED-GOVERNOR.

SPECIFICATION forming part of Letters Patent No. 326,881, dated September 22, 1885.

Application filed January 26, 1885. (No model.)

To all whom it may concern:

Be it known that I, ROBERT MCKENNA, a citizen of the United States, residing at White, in the county of Shelby and State of Tennessee, have invented a new and useful Speed-Governor, of which the following is a specification.

My invention relates to a duplex ball speed-governor; and it consists in the construction, arrangement, and combination of parts substantially as hereinafter set forth, the object being to produce a speed-governor which shall be simple and cheap of construction, efficient of service, and not liable to get out of order. I attain these objects by the mechanism illustrated in the accompanying drawing, which is a vertical sectional elevation of my duplex ball speed-governor.

Similar letters refer to similar parts throughout the drawing, the figure 2 being placed near the upper right-hand corner of the letters in part 2 to designate the parts of part 2 from those of part 1.

A is the frame, B the driving-shaft, C the miter-gear, D the main shaft, E the arms, O the arm-pins, F the balls, and M the valve-stem of my duplex ball speed-governor, all of which are constructed, arranged, and, excepting valve-stem M, operated in a manner similar to that in which like parts are constructed, arranged, and operated in an ordinary ball speed-governor.

A novel and important principle of construction and arrangement will now be explained in connection with the device as described.

A flanged hub, h, sleeves onto valve-stem M, and is secured thereon by a set-screw, S. A threaded stud, g, screws into a threaded hole in the pivotal ends of arms E, and is horizontally adjustable therein with reference to flange K on flanged hub h, and can be retained after adjustment by a jam-nut, n. A hub, p, having a thread on its outside surface, sleeves onto the lower part of valve-stem M, and is secured thereon by a set-screw, V. Hub p is adapted to screw up and down in a nut, T, which latter is secured in frame A.

The device as now described constitutes part 1 of my duplex ball speed-governor.

A frame, A², miter-gear, C², main shaft D², arms E², arm-pins O², balls F², studs g², jam-nuts n², flanged hub h², flange K², set-screw f², and valve-stem M², when combined and arranged with part 1, substantially as set forth, 55 constitute part 2 of my duplex ball speed-governor. Parts 1 and 2 are rotated by one and the same driving-shaft, B, part 2 being rotated in the reverse direction from that of part 1. One and the same valve-stem, M, extends vertically through the center of both parts 1 and 2, and is rotated by part 1 when necessary to open the governor-valve to regulate the speed of the engine, and by part 2 when necessary to close the governor-valve to regulate the speed 60 of the engine. When the engine is in motion at the desired speed, balls F will swing at an elevation that will bring the free ends of studs g and g² close to the outer edge of flanges K and K². A further outthrow of balls 65 F² will press studs g² toward flanged hub h², causing stud g² to engage with flange K². While thus engaged stud g², which rotates with main shaft D², will rotate valve-stem M², causing valve-stem M to screw down in nut 70 T, thereby closing the governor-valve, so as to regulate the speed of the engine. An infall of balls F will press studs g toward flanged hub h, causing stud g to engage with flange K. While thus engaged stud g will 75 rotate valve-stem M², causing valve-stem M to screw up in nut T, thereby opening the governor-valve, so as to regulate the speed of the engine. When valve-stem M moves in either direction to the full extent of its travel, the 80 engaged flange K or K² will have passed above or below the propelling-stud g or g², and valve-stem M will have ceased to rotate.

By adjusting studs g and g² a change of the speed of the engine can be attained.

I claim—

1. The combination of flanged hub h, flange K, set-screw S, studs g, jam-nuts n, hub p, nut T, and set-screw V, with frame A, driving-shaft B, miter-gears C, main shaft D, arms E, 95 arm-pins O, balls F, and valve-stem M, substantially as set forth.

2. The combination of part 2, consisting of frame A², miter-gear C², main shaft D², arms E², arm-pins O², balls F², studs g², jam- 100

nuts n^2 , valve-stem M, flanged hub h^2 , flange K ^{2} , and set-screw S ^{2} , with part 1, consisting of frame A, driving-shaft B, miter-gear C, main shaft D, arms E, arm-pins O, balls F, 5 studs g, jam-nuts n, valve-stem M, flanged hub h, flange K, set-screw S, threaded hub p, set-screw V, and nut T, when constructed,

arranged, and combined substantially as set forth.

ROBERT MCKENNA.
